ISAMU HOSOI, OF OSAKA-SHI, JAPAN

GEARING FOR SOUND-REPRODUCING MACHINES

Application filed April 23, 1928, Serial No. 272,303, and in Japan April 28, 1927.

This invention relates to improvements in sound reproducing machines of the disc-record type and has for its object to provide improved means whereby the turn-table may be driven by means of the governor controlled spring motor at uniformly increasing angular speed, so that the linear speed of the record surface relative to the reproducing needle is constant.

10 The invention is illustrated in the accompanying drawings in which:

Fig. 1 is a side elevation of a structure of the improved means, the machine being fragmentally shown.

15 Fig. 2 is a plan view of a structure of said means.

Fig. 3 is an end view of Fig. 1.

Fig. 4 is an end view of the carriage for the driving friction wheel.

20 Fig. 5 is a plan view of the machine in smaller scale.

Referring to the drawings, the friction wheel 2 for driving the turn-table 1 on engaging with the under side of said turntable is provided with a boss 3 which is formed with a projection on the inside of its bore. Said friction wheel is mounted on a shaft 4 which is formed with a longitudinal groove adapted to slidably receive said projection in the boss 30 of said friction wheel, in such a manner that said friction wheel may be driven with said shaft while longitudinal movement on said shaft is allowable. Said shaft is pivotally mounted at points 6, 6 on a frame 5 and carries 35 a spur gear 7 which meshes with a spur gear 8 secured on one end of a shaft 9 driven at constant speed from the governor controlled spring motor which forms no part of the invention. Said frame is swingably supported 40 by means of pins 10, 10 fixed on another suitable frame 12 fixed on under side of the top cover 11 of the usual box or case of the machine and a spring 13 pending from said top cover fixed on under side thereof. The 45 pins 10, 10 are disposed on the straight line corresponding to the common tangent at the touch point of the pitch circles of the gears 7 and 8, so that the frame 5 may be swung on said pins through some extent as desired 50 by depressing one end thereof against ten-

sion of the spring 13 without causing said gears to disengage with each other and so as not to interfere with their co-operation. To mechanically feed the friction wheel 2 on its shaft 4 as the turn-table 1 rotates, a carriage 14 is provided, which comprises a body member 15 carrying a nut member 16 and fork member 17. Said body member is provided with bosses 18, 19 and loosely mounted on a guide rod 20 and feed screw 21 to allow longitudinal movement thereon. Said fork member is uprightly fixed to the body member 15 and adapted to engage with an annular groove 22 formed on the boss 3 of the friction wheel 2. Said nut member is provided with slots 23 and 24, of which the former is adapted to receive a holding pin 25 fixed to the body member 15 and the latter is formed at its bottom with screwthread adapted to engage with the feed screw 21 and held in position by means of a spring 26 always abutting the upper end thereof on the under side of the boss 3 of the friction wheel 2, as clearly seen in Fig. 4. Fixed to one end of the feed screw 21 is a bevel gear 27 which meshes with a bevel gear 28 fixed to the lower end of the vertical spindle 29 upon which the turn-table 1 is pivoted, so that rotation of said turn-table causes the friction wheel 2 to be fed through the feeding means as described above. 30 is a push-button and is provided with a spindle 31 downwardly extending through the top cover 11 of the machine case, the lower end abutting on the frame 5 near the point supported by the spring 13, as clearly seen in Figs. 1, 2 and 3. Upon depressing said push button, the frame 5 will be downwardly swung on the pins 10, 10 and cause the friction wheel 2 to disengage with the under side of the turn-table 1, at the same time the nut member 16 of the carriage 14 will be depressed against the spring 26 and will disengage with the feed screw 21, so that said carriage may be freely shifted on the guide rod 20. Said carriage may be shifted by means of a curved lever 32 which is formed with a slot 33 at its lower end to receive a pin 34 fixed on the boss 18 of the body member 15 of said carriage, and is fixed at its upper end to the 100

lower end of the shaft 36 of a sector gear 35 operatively mounted on the under side of the top cover 11. Said sector gear meshes with a pinion 37 which is fixed at the under side of the top cover 11 to the lower end of a shaft 38 upwardly extending through said top cover and provided with a handle 39 on the upper end thereof, as clearly seen in Figs. 1 and 2, so that the carriage may be shifted by rotating said handle when the nut member 16 is disengaged with the feed screw 21. In order to indicate the position of the friction wheel 2 relating to the turn-table 1, an index 40 is fixed to the shaft 38 of the handle 39 to co-operate with a dial-plate 41. In order to indicate the relative positions of the friction wheel 2 and the tip of the reproducing needle on the record, an index 42 is fixed to the sound tube 43 to co-operate with a dial plate 44 fixed to the upper side of the top cover 11, the graduation being preferably made in such a manner that both indications are just the same when the friction wheel is positioned just below the tip of the reproducing needle on the record.

In operation, the turn-table 1 is driven by the friction wheel 2 which is yieldingly engaged with the under side of said turn-table under proper pressure at all times on account of the means for supporting said friction wheel as described above, and said friction wheel is fed to traverse across said turn-table as said turn-table rotates, so that said turn-table will be driven at uniformly increasing angular velocity when said friction wheel is driven from the spring motor at a certain constant speed.

For use of an ordinary record, the turn-table 1 may be driven at a certain constant angular velocity by locating the friction wheel 2 on the blank portion of the feed screw 21 toward its center.

With the arrangement of parts above described, a reproducing disc record having a greater capacity than ordinary records of the same dimensions, in which those portions or undulations of the spiral sound grooves formed by sounds of equal duration are of substantially equal length without regard to the position thereof in the sound groove, may be effectively reproduced, and also ordinary records may be effectively reproduced, if desired.

Having now particularly described and ascertained the nature of my said invention and in what manner the same is to be performed, I declare that what I claim is:—

1. In a machine for reproducing sound, a turn-table, a motor driven shaft, a friction drive wheel for the turn-table slidably mounted on said shaft and rotating therewith, motor driven intermeshing gears one of which is carried by said shaft, a supporting frame for said shaft, pins arranged in alinement with the common tangent at the

touch point of pitch circles of said gears and supporting the frame for pivotal movement whereby to allow a swinging movement of said frame on said pins while maintaining the gears in mesh, and means for feeding said friction wheel axially along the motor driven shaft during turning movement of the turn-table.

2. A machine for reproducing sound as claimed in claim 1, characterized in that said feeding means comprises a feed screw operated by the turn table, a carriage including a body member movable on the feed screw, a member carried by said body member engaging the friction wheel, and a nut member engaging said feed screw, said nut member being disengaged from said screw upon depression of the friction wheel below normal operative position.

In testimony whereof I affix my signature. ISAMU HOSOI.
